UNITED STATES PATENT OFFICE

GEORGE I. LEONARD, OF LOS ANGELES, CALIFORNIA, ASSIGNOR TO LEONARD ROTARY PUMP CORPORATION, OF LOS ANGELES, CALIFORNIA, A CORPORATION OF CALIFORNIA.

REFRIGERATING APPARATUS.

1,193,161.

Specification of Letters Patent.

Patented Aug. 1, 1916.

Application filed April 16, 1914. Serial No. 832,367.

To all whom it may concern:

Be it known that I, GEORGE I. LEONARD, a citizen of the United States, residing at Los Angeles, county of Los Angeles, and State of California, have invented a new and useful Refrigerating Apparatus, of which the following is a specification.

My present invention relates to an improvement in refrigerating apparatus of the type exemplified in Letters Patent of the United States No. 1,086,675, dated February 10, 1914; and it relates more particularly to improvement of the machine of said Letters Patent.

15 In the accompanying drawing, Figure 1 is a partly-broken view showing the refrigerator-tank and the pump in section and the pump-driving motor in elevation; Fig. 2 is an end view of the pump with the inner head removed; Fig. 3 is a top plan view of the pump presenting the spiral gears thereof through an opening in the case; Fig. 4 is an enlarged sectional view of the valved expansion-chamber shown in Fig. 1 and Fig. 25 5 is a view diagrammatically showing the whole apparatus.

The tank or casing 4 for containing the sealing and refrigerating liquids employed, and which is represented as being supported 30 on a base 22, is of the preferred form shown and is provided with a head fastened in place by screw-bolts and carrying a pressure-gage.

About an opening in one side of the tank, 35 near its lower end, is formed an outwardly projecting flange 25. The pump herein represented is of the kind shown and described in the aforesaid Letters Patent, involving an open case 5 containing inter- 40 meshing gears 7 mounted on shafts. On the outer end of the pump-case 5 is formed a flange 19, which is bolted to the face of the flange 25 to support the pump stably in its operative position, wherein it seats in the 45 flange and projects horizontally through the tank-wall into the tank near its bottom. A head 6 is bolted to and closes the inner end of the pump-case and affords bearing for the corresponding ends of the two gear- 50 shafts, one of which, denoted by the reference numeral 8, extends through a stuffing-box or gland 9 on the outer end of the case 5 and alines with and is coupled to the shaft of an electric motor 20 supported on the 55 base 22, as shown in Fig. 1. A suction or

intake port is provided at 10, to which a suction-line leads containing an upwardly opening check-valve 11; and a branch pipe 12 connects this line at a point below the check-valve therein with a pipe 18 leading 60 from a valve expansion-chamber clearly illustrated in Fig. 4 and the construction and operation of which are hereinafter described. A valved pipe 13, for the pressure-line, leads from the tank to this expansion- 65 chamber for carrying the refrigerant thereto. A refrigerator-coil or chamber (not shown) is to be interposed between the pipe containing the check-valve 11 and a pipe 17 leading from the expansion-chamber. As 70 means for condensing the refrigerant in the tank, a coil 14 is shown depending therein from its head, through which the coil-ends pass, with one of which, as that denoted by the reference-numeral 21, connection may be 75 made with a suitable water-supply for flowing condensing water through the coil.

The level of the sealing liquid in the tank is indicated at 23 and that of the refrigerant is indicated at 24, in Fig. 1. 80

The manner thus described for combining the rotary pump with the tank greatly simplifies and cheapens the construction while stably supporting the pump in its operative position without other support for the purpose; and, besides, it facilitates assembling 85 and separation of the parts.

The valved expansion-chamber involves a casing preferably formed in two parts, as shown, screwing together to clamp between 90 them a diaphragm 16 having secured to its center a needle-valve 15^a. The needle-valve controls a minute orifice or port 15 in a valve-seat 15^b in the inner end of a nipple 18^b, at which the pressure-pipe 13 is connected with the expansion-chamber at the side of the diaphragm from which the pipe 17 of the suction-line extends. A nipple 18^a is provided on the part of the casing at the opposite side of the diaphragm, for connecting therewith the pipe 18, which is to be understood as being connected with the branch-pipe 12, of which it is intended to be a continuation. 95 100

In the operation of the apparatus, working of the motor 20 to actuate the pump circulates the liquid refrigerant from the tank through the circulating system, thus through the pressure line 18 into the expansion-chamber, whence it passes by way of the 110

2

pipe 17 through the aforesaid refrigerator-coil and enters, in expanded or gaseous condition, by way of the pipe containing the upwardly-seating check-valve 11, past the latter, to the suction-port or intake 10. The expanded liquid is thus sucked into the pump-case to be compressed between the teeth of the gears therein, whence it enters, in compressed condition, into the sealing liquid in the tank to be cooled and liquefied by the relatively low temperature in the latter produced by the condenser 14. The liquefied refrigerant rises through and surmounts the sealing liquid, being of lesser gravity than the latter; though it may, obviously, be of a relatively heavy variety, causing it to sink beneath the sealing liquid to be taken thence into the pressure-line of the apparatus. While the pump is thus operating, the suction it exerts on the line 12, 18 operates the diaphragm 16 to withdraw the needle-valve 15^a and slightly open the port 15 for admission of the refrigerant from the pressure line into the expansion-chamber. When the pump stops, the pressure in the tank forces the sealing liquid through the pump and by way of the line 12, 18 into the chamber behind the diaphragm to exert pressure against the latter to close the needle-valve and stop circulation of the refrigerant; and when the pump is again started, its suction action on the line 12, 18 withdraws this pressure and restores the circulation.

35 The valved expansion-chamber thus renders the apparatus automatic in its operation, avoiding all necessity of turning on and off by hand, since the needle-valve is set to operate under a given amount of work to be performed. This is of importance, because if the valve did not close, the entire system of cooling-pipes would fill with the refrigerating liquid and thus throw a heavy load on the motor and pump in evaporating off the large body of refrigerant before the regular expansion would take place under the control of the needle-valve.

In order to effect a better sealing action on the pump, I provide one or more holes 26 (Fig. 2) through the pump-case at a suitable point between the intake and exhaust-ports to admit a small portion of the sealing liquid from the pressure side.

Any suitable refrigerant may be used, for operating my improved apparatus, of a gravity so differing from that of the sealing liquid that it will rise above or sink below the latter. Thus rhigolene works well as the refrigerant with glycerin as the sealing liquid; ammonia may be used as the refrigerant with a suitable oil for sealing; and

sulfur dioxid may be used as the refrigerant with oil, but being heavier than the oil will sink beneath it and have to be taken into the pressure-line from below the oil-body. 65

What I claim as new and desire to secure by Letters Patent is:—

1. In a refrigerating apparatus employing an expansible fluid refrigerant, the combination of a tank having a pressure-outlet 70 and a side-opening provided with an outer flange forming a pump-seat, a rotary motor-driven pump having a flange on the outer end of its case and seating in said tank-flange to extend said case horizontally into 75 the tank with the case-flange abutting against and secured to the tank-flange face, said pump having an outlet within the tank and an intake, and a circulating system for the refrigerant connecting said pressure-outlet 80 with the pump-intake.

2. In a refrigerating apparatus employing an expansible fluid refrigerant, the combination of a tank having a pressure-outlet and a side-opening provided with an outer 85 flange forming a pump-seat, a rotary motor-driven pump, having a flange on the outer end of its case and seating in said tank-flange to extend said case horizontally into the tank with the case-flange abutting 90 against and secured to the tank-flange face, said pump having an outlet within the tank and an intake, a head secured to the inner end of the pump-case and forming bearings for shafts of the rotary-pump members, and 95 a circulating system for the refrigerant connecting said pressure-outlet with the pump-intake.

3. In a refrigerating apparatus employing an expansible fluid refrigerant and a 100 sealing liquid, the combination of a tank for containing said refrigerant and liquid and having a pressure-outlet, a rotary motor-driven pump in the tank and having its outlet therein and an intake, a pressure-line 105 leading from said pressure-outlet, a valve-seat at the discharge-end of said line containing a minute orifice, a casing containing a chamber connected with said discharge-end, a diaphragm in said casing dividing it 110 into chambers and carrying a needle-valve for controlling said orifice, a suction-line leading to the pump-intake from the chamber at one side of the diaphragm and containing a check-valve, and a branch suction-line connecting said suction-line between the check-valve and the pump with the chamber at the opposite side of the diaphragm. 115
